UNITED STATES PATENT OFFICE.

THOMAS FOSTER WHITE, OF SALEM, KANSAS.

WRENCH.

SPECIFICATION forming part of Letters Patent No. 297,209, dated April 22, 1884.

Application filed September 8, 1883. (No model.)

To all whom it may concern:

Be it known that I, THOMAS F. WHITE, a citizen of the United States, residing at Salem, in the county of Jewell and State of Kansas, have invented a new and useful Wrench, of which the following is a specification, reference being had to the accompanying drawings.

This invention relates to wrenches; and it has for its object to provide a device which will be readily convertible into a nut or pipe wrench at a moment's notice.

To this end, it consists in certain details of construction and combination of parts, as hereinabove set forth, and particularly pointed out in the claims.

In the accompanying drawings, Figure 1 is a perspective view of my device adjusted as a nut-wrench. Fig. 2 is a similar view when adjusted as a pipe-wrench, and Fig. 3 is a longitudinal section of Fig. 1.

The same letters refer to corresponding parts in the several figures.

For purposes of description, the end of the wrench farthest from the handle is the forward end, and the side on which the jaws are the front side.

Referring to the drawings, A designates the shank of an ordinary wrench, provided at the forward end with stationary jaw B and at the opposite end with a handle, C.

D designates the sliding jaw, provided with an opening, d, for the passage of the shank, and having a rearward extension, E, to which is pivoted or jointed a forward extension, F, of a sliding sleeve, G, the latter sliding on the shank, and arranged to slide the jaw D toward or away from the stationary jaw. A flange, H, projects downwardly from the rear end of the sleeve G, and is formed with a groove, i, in its inner face, while a worm-wheel, I, longitudinally movable on the shank, engages with the groove in the flange, so as to cause the longitudinal movement of the sliding jaw carrying the sleeve. The circumference of the worm-wheel is provided with serrations or with a milled edge, in order to provide for the ready manipulation of said wheel. It will be seen that the extension F of the sleeve is bifurcated or slotted to receive extension E of the sliding jaw, said extension E readily fitting within and working in the slot, so that

the conversion from a nut to a pipe wrench can be easily performed. A spring, J, is secured to the front or upper face of shank A, and bears against the inner face of the sliding jaw, so as to press said jaw outward when working on pipe or round iron, and a pointed screw or rod, K, works through an opening, l, in the side of the sliding jaw, so as to engage with a longitudinal groove, L, formed on the side of shank A. This pointed screw or rod guides the sliding jaw when used as a nut-wrench, and also serves as a means for adjustment of the wrench from a wrench for nuts to a wrench for working on pipes or round iron. The inner faces of the jaws D B are serrated, milled, or provided with teeth to engage with the pipe or nuts in turning, said teeth or serrations extending in opposite directions on each jaw.

The operation of my invention can be readily understood from the foregoing description, taken in connection with the annexed drawings.

When used as a nut-wrench, the screw K is engaged with groove L and guides the sliding jaw and sleeve in its movements, the manipulation of worm-wheel I causing the sleeve to slide upon the shank, the said sleeve, by means of its connection with the sliding jaw, causing the latter to move longitudinally on the shank. Thus the turning of the worm-wheel regulates the distance between the jaws B D.

To change the nut-wrench into a pipe-wrench, the screw or rod K is first withdrawn from slot L, and since the lower or sliding jaw is jointed to the extension of the sleeve, and is, furthermore, forced toward the front side of the wrench by spring J, said sliding jaw will be thrown to the position shown in Fig. 2, and can then be used to turn pipes or round iron in making joints or like work.

When used as a pipe-wrench, the operation of worm-wheel I effects the movement of the sliding jaw and the sleeve in a similar manner as in a nut-wrench.

The advantages of my improved nut or pipe wrench are obvious, the construction being simple and durable, while the operation is effective.

The combination of a nut and pipe wrench into one device will prove of convenient use

to mechanics, since heretofore two different wrenches have been used to perform the functions of my single device. I thereby avoid the cost of the other wrench, while the great convenience arising from its use will be appreciated by all.

It is apparent that numerous modifications can be resorted to in the foregoing without departing from the spirit or scope of my invention.

Having described my invention, I claim as new—

1. In a wrench, the shank provided with a slot or groove in its side, in combination with the sliding jaw pivoted or jointed to a sliding sleeve, and a pointed screw or rod working through the side of the jaw and engaging with the slot or groove, as and for the purpose set forth.

2. In a wrench, the shank A, carrying stationary jaw B, and provided with a longitudinal groove in its side, in combination with the sliding jaw pivoted or jointed to a sliding

sleeve, and having a pointed screw or rod engaging with the longitudinal groove, and a spring secured to the shank and bearing against the inner face of the sliding jaw, substantially as and for the purpose set forth.

3. In a wrench, the shank A, provided with a longitudinal groove or slot in its side, in combination with the sliding jaw formed with a rearward extension, a sleeve provided with a forward extension, which is pivoted or jointed to the said rearward extension, a pointed screw or rod working through the sliding jaw and engaging with the groove in the shank, and a spring bearing against the inner face of the sliding jaw, as and for the purpose set forth.

In testimony that I claim the foregoing as my own I have hereto affixed my signature in presence of two witnesses.

THOMAS FOSTER WHITE.
